[57] CLAIM

The ornamental design for a bulb for a high voltage detector, as shown and described.

DESCRIPTION

FIG. 1 is a side elevational view of the bulb for a high voltage detector, the opposite side being a mirror image thereof;

FIG. 2 is a top plan view of the bulb;

FIG. 3 is a bottom plan view of the bulb;

FIG. 4 is a right end elevational view of the bulb, the left end view being a mirror image thereof.

The electrode in each end of the bulb is cylindrical in cross section.

*FIG. 1**FIG. 2**FIG. 3**FIG. 4*
